BOWLING BALL GRIP MEASURING DEVICE

Albert J. Lorenz, Clifton, N. J., assignor to American Hard Rubber Company, New York, N. Y., a corporation of New York

Application December 2, 1954, Serial No. 472,710

1 Claim. (Cl. 33—174)

The present invention relates to a bowling ball grip measuring device and more particularly to such a device in the form of a substantially spherical structure approximating the weight of a conventional ball and made up in two portions, each of which is a part of a sphere of the same radius, the radius being that of the conventional bowling ball aforesaid. These portions are something less than complementary to each other, so that they may be arranged around a common center, one of these portions to be provided with one or more thumb holes and the other to be provided with one or more pairs of finger holes. Thus by having the thumb holes of different sizes and the finger holes likewise of different sizes, and further by having the portions relatively movable with respect to each other, it is possible to provide an almost infinite variety of combinations of different size holes, different arrangement of holes and different spans between the holes, so as to suit the grip of any bowler. The device is arranged so that one portion may be adjusted with respect to the other and the adjustment secured in a fixed position, so that the person trying out the device may actually handle it as a bowling ball to get the complete "feel" thereof and to assure the accuracy of the adjustment. The size and position of the holes may then be ascertained by suitable measurement and a conventional bowling ball prepared by drilling with this size and arrangement of holes for peculiar use of the person testing it. In this way a person is assured of a bowling ball which is peculiarly adapted for use by the person for whom it is intended.

Prior art grip measuring devices have been devised which purport to do all the various things above described. These devices have been somewhat short of fully satisfactory, however, in that the means by which the adjustment between the two portions of the ball or device has been insecure, so that it has been difficult and sometimes impossible, particularly when the prior art devices have been somewhat worn, to hold the two portions of these grip measuring devices in an adjusted position during an actual tryout of the ball device by bowling.

The present invention seeks to overcome this difficulty by providing an improved means for connecting the two portions of the device and particularly for securing the adjustment therebetween against inadvertent slippage, so that the device, once the adjustment is made and secured or locked, may be used as an actual bowling ball and a fair and complete test made of the adjustment.

Summarizing the present invention, therefore, it comprises the combination in a device as above set forth of a new and improved means for connecting the two portions thereof and for securing or locking any adjustment which may be made as between such portions. This means comprises a substantially annular member secured to one of the ball portions and having a part in the form of a hollow sphere, which may be engaged on both its inner and outer spherical surfaces by gripping means secured to or forming a part of the other portion of the

2

ball device, so as to lock the two portions of the ball device against any inadvertent and undesired relative movement. The annular member preferably is formed of rigid metal at least as to its core portion, and has at least one, and preferably both, its inner and outer spherical surfaces coated with a suitable rubber-like compound, which is softer than the spherical surfaces which grippingly engage it respectively at the adjusted position of the parts and when the adjustment is locked as aforesaid. Particularly, the coating on the annular member is provided, preferably on both surfaces, and is a rubber composition somewhat softer than the rubber composition of which the ball portions may be formed and, of course, softer than the metal member, which is used as hereinafter set forth, to engage the inner spherical surface of the annular member. One or both of these engaging surfaces may be roughened, serrated, knurled or somehow formed with surface irregularities which will cooperate with the relatively soft coating on one or both surfaces of the annular member to assure full locking when the portions of the ball device are secured to one another after they have been adjusted to a desired point. Inasmuch as the annular member aforesaid has its spherical surfaces concentric with the spherical surfaces of the two ball portions, the adjustment may be secured at any desired adjusted position.

Other and more detailed features of the invention will be set forth hereinafter and will be better appreciated by reference to the accompanying drawings, in which:

Fig. 1 is a view in elevation of a bowling ball grip measuring device in accordance with the present invention;

Fig. 2 is a transverse sectional view of the device taken substantially on the line 2—2 of Fig. 1;

Fig. 3 is a fragmentary detailed view in transverse section on the line 3—3 of Fig. 2;

Fig. 4 is a view partly in elevation and partly broken away and in vertical section of the metal portion of the annular member hereinafter described in detail, prior to the application thereto of the relatively soft rubber-like composition to form the inner and outer gripping surfaces;

Fig. 5 is a view in elevation of the central gripping means and its stem;

Fig. 6 is a view similar to the lower portion of Fig. 5 showing a modified form of surface of the spherical portion of the gripping means, particularly a knurled surface; and

Fig. 7 is a fragmentary view, substantially in central section as in Fig. 2, of the upper portion as shown in Fig. 2 of the ball device, showing a modified form of inner surface conformation to give a better grip with respect to the relatively softer outer surface of the annular member.

Turning now to the accompanying drawings, in which is shown a preferred embodiment of the invention, there is illustrated a bowling ball grip-measuring device including a first portion 10, which is provided as shown with a plurality of thumb holes 11 and a portion 12 provided with a plurality of pairs of finger holes 13. The two portions 10 and 12 are something less than complementary to each other as indicated by the annular space of outwardly diverging width shown at 14. This space is closed at its outer periphery by a substantially annular band member 15, preferably of metal, and preferably formed in two or more portions in a manner not illustrated, but which will be obvious to those skilled in the art. Each portion of the band member 15 is secured by means not shown to the ball portion 12, such means preferably comprising suitable screws or similar devices. Also as shown, the band member 15 has an outer contour

which is a part of a spherical surface concentric with the spherical outer surfaces of the ball portions 10 and 12. The ball portions are suitably recessed as indicated at 16 and 17 to receive the band member 15. This permits the device as a whole to be used as a bowling ball, once the portions 10 and 12 thereof have been set to any predetermined adjusted position and the setting or adjustment therebetween secured by the means hereinafter described and which particularly form the subject matter of the present invention.

For holding the ball portions 10 and 12 in their assembled position and for securing them together at any adjusted position, there is provided novel means according to the present invention. One element of these means comprises an annular member 18, which is preferably formed of metal at least as to the core portion thereof. The member 18 is secured to the ball portion 10, for example, by intermeshing threads as shown at 19. In order practically to permit the member 18 to be positioned and removed from the ball portion 10, the outer peripheral flange thereof, shown at 20 in Fig. 4, is provided with at least two substantially diametrically positioned apertures 21 which may be engaged by the pins of a suitable spanner type wrench. One of these holes, or an additional similar hole or aperture, may be threaded and provided with a set screw as shown at 22 (Fig. 2) to lock the member 18 against inadvertent unscrewing movement, the set screw 22 extending into engagement with the subjacent part of the ball portion 10 as shown.

The member 18 is provided with inner and outer gripping surfaces 23 and 24 for engagement with suitable gripping means hereinafter described. These surfaces are preferably formed as portions of spherical surfaces concentric with the outer spherical surfaces of the ball portions 10 and 12 at the operative position of the parts as shown in Fig. 2.

The outer spherical surface 24 of the member 18 is preferably engaged by a complementary inner spherical surface 25 of the ball portion 12 as shown. The inner spherical surface 23 of the member 18 is engaged by a spherical surface 26 of a gripping means generally indicated at 27, which is preferably of suitable metal, such as steel, and which is provided with a stem portion 28 extending through a suitable aperture 29 in the ball portion 12. The outer end portion of the stem portion 28 is threaded as illustrated at 30 and is engaged by a suitable nut 31. As shown, the nut 31 has an outer spherical surface arranged concentric with the outer spherical surface of the ball portion 12 when the nut is in position in a recess 32 formed in this ball portion, as shown in Fig. 2. The nut is also provided with one or more diametrically arranged sets of apertures 33, which may be engaged by the pins of a suitable spanner wrench for rotating the nut for tightening and loosening the adjustment, as will now be obvious from the drawings and the foregoing description.

Means are also provided in conjunction with the parts thus far described for preventing relative rotation between the gripping means 27 and the ball portion 12. For this purpose the stem 28 may be provided with a laterally extending pin 34, which is received in a suitable radial slot 35 formed in the ball portion 12, as best shown in Fig. 2.

While the device as hereinabove described is normally effective for accomplishing the purposes set forth, it has been found that the best type of gripping as between mating spherical surfaces is where these surfaces are of material of different hardnesses. Thus, for example, if the ball portions 10 and 12 are formed, as is now contemplated, of a hard rubber composition material, then the member 18 may be wholly of metal and may have its outer spherical surface wholly of metal and provide relatively different hardnesses at the surfaces 24-25, the metal being harder than the hard rubber of which the ball portion 12 is formed.

On the other hand, it has been found to be a desirable type of construction to form the inner and outer surfaces of the member 18 of a relatively softer rubber composition or rubber-like material, which may be applied onto the metal shell or core of the member 18 and be rigidly secured thereto, for example, by vulcanizing it in place, the member 18 being provided with a plurality of grooves as indicated at 36 and 37 (Fig. 4). Thus the member 18, as shown, may have an inner relatively soft friction layer 38 and an outer relatively soft friction layer 39. The composition of both the friction layers 38 and 39 may be the same or different as desired. In a preferred embodiment, however, this composition is the same inside and outside and in each instance is somewhat softer (52-60 as measured by Shore "D" durometer) than the composition of which the ball portions 10 and 12 are formed (79-84 as measured in the same way). By the same token, the layer or covering 38 will be softer than the metal of which the gripping means 27 is formed. Furthermore, if desired, the inner surface 25 of the ball portion 12 may be provided, as shown in Fig. 7, with a plurality of grooves as indicated at 40 formed as annular grooves or formed in some other fashion, for example, intersecting grooves. These grooves or non-uniform configurations, of which the grooves shown in Fig. 7 are but one example, may cooperate with the relatively soft coating layer 39 to give assured gripping at any adjusted position of the parts. In a similar way, the outer surface 26 of the ball or spherical portion of the gripping means 27 may be formed as diagrammatically illustrated in Fig. 6 with suitable non-uniform surface configurations as the knurling 41 indicated in that figure. This non-uniform surface configuration may also cooperate with the relatively soft inner layer 38 of the member 18 to give a tight grip when the parts are suitably adjusted and the adjustment secured or locked by tightening the nut 31.

While there is illustrated and has been described herein but one principal embodiment of the invention with minor variations as to certain detailed features, other equivalents will suggest themselves to those skilled in the art from the foregoing disclosure. I do not wish to be limited, therefore, except by the scope of the appended claim, which is to be construed validly as broadly as the state of the prior art permits.

What is claimed is:

In a substantially spherical bowling ball grip measuring device for determining the characteristics of holes for bowling balls for different persons respectively, said device having two ball portions, each of which is a part of a sphere of the same radius, said radius being substantially that of a standard bowling ball, said portions being sufficiently less than complementary to each other so that when they are arranged with a common center, one of said portions may be moved about said common center with respect to the other of said portions, at least one thumb hole arranged in one of said portions, at least one set of finger holes arranged in the other of said portions; connecting and adjustment-securing means between said portions, comprising a substantially annular member having concentric inner and outer substantially spherical surfaces and being rigidly connected to one of said portions in such manner that said surfaces will be concentric with the center of said one portion, the other of said portions having an annular interior surface portion formed as a part of a sphere concentric with the outer surface of this other portion and having an inner radius substantially equal to the radius to the outer surface of said substantially annular member, gripping means adjustably securable to said other portion and having a part formed as a part of a sphere having a radius substantially equal to the radius of the inner spherical surface of said annular member, means for forcing said gripping means to grip the inside surface of said annular member and thereby to hold the outer surface thereof against the inner spherical

surface portion of said other portion of said device; said annular member being built with a core portion of rigid metal, which is threadedly secured to one of said portions of said device with said substantially spherical surfaces thereof concentric with both said portions of said device at the operative position of the parts, each of said substantially spherical surfaces of said annular member being formed as a coating of a rubber-like composition which is relatively softer than the material of which said portions of said device are formed, said coatings being rigidly secured to the core portion of said annular member; said other portion of said device having its inner spherical surface for contact with the outer spherical surface of said annular member formed with a plurality of grooves for engagement with the relatively soft rubber-like composition forming the outer coating of said annular member; and said gripping means, which is adjustably secured to said other portion of said device, having its outer substantially spherical surface, which is arranged for contact with the inner spherical surface 20 of said annular member, formed as a knurled surface, so as to give a tight gripping engagement with the rela-

5
10

tively soft coating forming the inner spherical surface of said annular member; said gripping means having a stem portion extending through an aperture in said other portion of said device and provided with means for preventing relative rotation between said stem portion of said gripping means and said other portion of said device, and means cooperating with said stem portion for relatively moving said gripping means in a direction in alignment with said stem portion, so as to grip said annular member between the spherical part of said gripping means and the inside of said other portion of said device.
